UNITED STATES PATENT OFFICE

HENRY F. CUSHNER, OF BROOKLYN, NEW YORK

DESIGN FOR A CAR FOR AMUSEMENT DEVICES

Application filed September 23, 1930. Serial No. 37,058. Term of patent 14 years.

To all whom it may concern:

Be it known that I, HENRY F. CUSHNER, a citizen of the United States of America, and a resident of Brooklyn, in the county of Kings and State of New York, have invented a new, original, and ornamental Design for a Car for Amusement Devices, of which the following is a specification, reference being had to the accompanying drawing, forming part thereof.

The figure is a perspective view of a car for amusement devices.

The design consists of the platform upon which is mounted a passenger carrying car in imitation of a baby carriage. A standard projects upwardly from the platform and

forms the support for a seat upon which a figure in a sitting position rests the figure having its hand upon the handle of the baby carriage.

The device is of the type used in amusement parks, the baby carriage is adapted to be occupied by a passenger, and the device is under control of the steering wheel which is shown as projecting upwardly and rearwardly of the baby carriage from the forward part thereof.

I claim:

The ornamental design for a car for amusement devices, as shown and described.

HENRY F. CUSHNER.
